UNITED STATES PATENT OFFICE.

ALBERT J. RICHARDS, OF SEATTLE, WASHINGTON, ASSIGNOR OF ONE-HALF TO A. C. DE NISSON, OF SEATTLE, WASHINGTON.

VAPORIZER.

1,338,398.

Specification of Letters Patent. Patented Apr. 27, 1920.

Application filed February 19, 1919, Serial No. 278,104. Renewed March 13, 1920. Serial No. 365,611.

To all whom it may concern:

Be it known that I, ALBERT J. RICHARDS, a citizen of the United States, residing at Seattle, in the county of King and State 5 of Washington, have invented a certain new and useful Improvement in Vaporizers, of which the following is a specification.

My invention relates to improvements in auxiliary air inlet valves for internal combustion engines and the object of my improvement is to provide an auxiliary air inlet valve of a cheap and simple form of construction that is reliable in operation and that is adapted to be opened by suction 10 produced within the pipe to which the valve is connected and to be closed by a spring disposed within the valve.

The device is particularly adapted for use on internal combustion engines and may be 20 connected with the manifold inlet pipe between the carburetor and the engine in such a position that it will be opened by the suction of the engine and will admit auxiliary air which will mix with the fuel charge 25 just prior to the admission of such charge to the cylinders thereby effecting a saving of fuel, tending to eliminate carbon deposits in the cylinders and making it possible to use lower grade fuel in the engine.

30 A further object is to provide an auxiliary air inlet valve of this class having a valve controlled fuel inlet pipe connected therewith through which liquid fuel, as gasoline, for priming or starting the engine 35 may be introduced.

The invention consists in the novel construction, adaptation and combination of parts as will be more clearly hereinafter described and claimed.

40 In the accompanying drawings Figure 1 is a view in side elevation of an internal combustion engine showing my air inlet valve connected with the manifold thereof;

Fig. 2 is an enlarged view in longitudinal 45 mid section of my automatic air inlet valve as it may appear when closed, a fragment only of the manifold inlet pipe being shown; and

Fig. 3 is a view partly in cross-section and 50 partly in elevation illustrating the valve in an open position.

Referring to the drawings, throughout which like reference numerals designate like parts, the numeral 5 designates an internal combustion engine that is provided

with a carburetor 6 which is connected to the cylinders of the engine by a manifold inlet pipe 7, the above mentioned parts being of the usual type and being shown merely to illustrate a convenient location 60 for the installation of my air inlet valve.

The air inlet valve proper comprises an inner pipe or tube 8 that is externally threaded at one end as at 9 so that it may be screwed into the manifold inlet pipe 7, a lock nut 10 being used to rigidly secure the tube 8 to the manifold inlet pipe 7.

The end of the tube 8 that projects into the manifold inlet pipe 7 is provided with an outwardly projecting cylindrical perforated member 11, shown in elevation in Fig. 2, such member being formed of a piece of thin perforated metal gauze rolled into cylindrical form and slipped into the end of the tube 8 so that it will project within the pipe 7 whereby the air that enters through the tube 8 will be caused to pass through the perforations in the member 11 and will mix thoroughly with the fuel in the inlet pipe 7.

The outer end of the tube 8 is disposed to telescope within a larger tube 12, the tube 12 being open at its inner end and closed at its outer end, and being provided adjacent its inner end with an elongated slot 13 through which may project a screw 14 that is screwed through the wall of the tube 8, the screw 14 serving as a means to prevent relative turning movement between the two tubes and as a stop to limit the end-wise movement of the tube 12 on the tube 8. In practice it is found convenient to have the screw 14 threaded through the wall of the tube 8 on one side and to allow it to strike against the wall of such tube 8 on the opposite side so that when the screw is tightened it will be frictionally held with sufficient force to prevent it from jarring loose.

The wall of the tube 8 is provided with an air inlet opening 15 and the wall of the tube 12 is provided with a similar air inlet opening 16 which normally does not register with the opening 15 but which will be caused by suction to register with such opening 15 105 when there is a partial vacuum in the pipe 7.

The outer tube 12 is normally held at the outer limit of its movement by a compression spring 17 one end of which rests against the outer end of the inner tube 8 and the 110

other end of which abuts against a movable plate 18 that is held in an adjusted position by a screw 19 that passes through the end of the outer tube 12, a lock nut 20 being provided for the purpose of locking the screw 19 in any desired position.

The tube 8 is provided adjacent its inner end with an upwardly directed branch 21 herein shown to be integral therewith but which if desired may be in the form of a separate shaped fitting. The branch 21 is provided at some suitable point throughout its length with a shut off valve 22 and is adapted to be connected at a point beyond the valve 22 with any suitable receptacle, not shown, that may contain liquid fuel, as gasolene for the purpose of priming or starting the engine with which this air inlet valve is connected. The branch 21 is particularly advantageous for admitting gas for priming and starting the engine in instances where lower grade oil as distillate or kerosene is used for fuel.

When this device is installed as hereinbefore described and the engine 5 is started a partial vacuum will cause the outer tube 12 to be drawn inwardly into a position approximately as shown in Fig. 3 so that the openings 15 and 16 will register and air will be admitted therethrough to mix with the fuel just prior to the entrance of such fuel into the cylinders of the engine.

The adjustment screw 19 makes it possible to vary the tension of the spring 17 so that the valve will be opened by any degree of vacuum that it is desired to have operate such valve.

Obviously changes in the precise form of construction and arrangements of the various parts of this auxiliary air inlet valve may be resorted to within the scope of the following claims.

What I claim is:

1. A valve of the class described comprising a smaller tube open at both ends and having a perforation in the wall thereof, a larger tube open at one end and closed at the opposite end and disposed to fit snugly over said smaller tube said larger tube hav-

ing a perforation in the wall thereof that is adapted to register with the perforation in said smaller tube when said larger tube is moved by suction exerted through said smaller tube, and said larger tube having a longitudinally extending slot in the wall thereof, a pin secured to said smaller tube and projecting outwardly through said slot to prevent relative turning movement between said two tubes and to limit the longitudinal movement of said larger tube on said smaller tube, a compression spring interposed between said two tubes to hold said tubes in such relative position that said perforations will not register when no suction is exerted through said smaller tube and means for adjusting said spring to vary the force of compression thereof.

2. A valve of the class described comprising a smaller tube open at both ends and having a perforation in the wall thereof, a perforated metal gauze projecting from one end of said smaller tube, a valve controlled inlet pipe connected with said smaller tube, a larger tube open at one end and closed at the opposite end and disposed to fit snugly over said smaller tube said larger tube having a perforation in the wall thereof that is adapted to register with the perforation in said smaller tube when said larger tube is moved by suction exerted through said smaller tube, and said larger tube having a longitudinally extending slot in the wall thereof, a pin secured to said smaller tube and projecting outwardly through said slot to prevent relative turning movement between said two tubes and to limit the longitudinal movement of said larger tube on said smaller tube, a compression spring interposed between said two tubes to hold said tubes in such relative position that said perforations will not register when no suction is exerted through said smaller tube and adjusting means for varying the force of compression of said spring.

In witness whereof I hereunto subscribe my name this 14th day of February, A. D. 1919.

ALBERT J. RICHARDS.
